ROBERT SCORER AND ROBERT HAM, OF TROY, NEW YORK, ASSIGNEES TO COX, CHURCH, AND COMPANY, OF SAME PLACE.

Design No. 3,474, dated May 4, 1869.

DESIGN FOR A COOK'S STOVE.

The Schedule referred to in these Letters Patent and making part of the same.

To all whom it may concern:

Be it known that we, ROBERT SCORER and ROBERT HAM, both of Troy, in the county of Rensselaer, and State of New York, have originated and produced a new Design for Cook-Stove, of which the following is a full, clear, and exact description, reference being had to the accompanying photograph, making a part of this specification.

This design consists of, and may be distinguished from all others by a certain series of bead, or raised moulding, *a* and *b*, on the hearth-plate, *A*, and a certain compound ornamental border-moulding, *c* and *e*, on the door-plates *B* and *C*, and a certain compound ornament, *d*, on the panel of the door-plates *B*, and a

certain compound ornament, *f*, on the panel of the door-plate, *C*, of a stove, the same being formed, arranged, and constructed so as to appear as represented by the aforesaid photograph.

What we claim as our invention, or production, and desire to secure by Letters Patent, is—

The design of the hearth-plate *A* and the door-plates *B* and *C* of a stove, herein set forth.

ROBERT SCORER.
